CLAIM

The ornamental design for the smart ignition system starter panel, as shown and described.

DESCRIPTION

FIG. 1 is a top perspective view of the smart ignition system starter panel in accordance with an embodiment of the present invention; and,

FIG. 2 is a top view of the smart ignition system starter panel of FIG. 1.

The broken lines of FIGS. 1 and 2 are illustrative of the visible environmental structure of the smart ignition system starter panel and form no part of the claimed design.

1 Claim, 2 Drawing Sheets See application file for complete search history.
